UNITED STATES PATENT OFFICE.

THOMAS H. MCQUOWN, OF CAMBRIDGE, MASSACHUSETTS, ASSIGNOR, BY DIRECT AND MESNE ASSIGNMENTS, TO ARTHUR ATWATER KENT, OF PHILADELPHIA, PENNSYLVANIA.

ELECTRIC-CIRCUIT CLOSER AND BREAKER.

1,109,689.

Specification of Letters Patent.

Patented Sept. 8, 1914.

Application filed November 24, 1906. Serial No. 344,612.

To all whom it may concern:

Be it known that I, THOMAS H. MCQUOWN, a citizen of the United States, and resident of Cambridge, county of Middlesex, State of Massachusetts, have invented an Improvement in Electric-Circuit Closers and Breakers, of which the following description, in connection with the accompanying drawing, is a specification, like letters on the drawing representing like parts.

This invention relates to a device for making and breaking an electric circuit. Devices of this character are commonly used in quite a variety of mechanism, such for instance as electric time recorders, electric speed recorders, ignition devices for internal combustion engines, etc.

In most of these mechanisms it is necessary to close the circuit momentarily only, the mere closing and breaking of the circuit serving to operate the mechanism with which the make-and-break device is used, and in order to prevent any unnecessary consumption of current it is desirable that as soon as the circuit has been closed it should be instantly opened again.

A device which is adapted to break the circuit instantly that it is closed is shown in my prior Reissued Patent No. 12,273, re-issued October 11, 1904.

In order to get the best result from these make-and-break devices it is also desirable that during the short interval of time that the contacts are closed together there should be a good electrical contact between the contacts, and also that when they are separated to break the circuit the separation should be instantaneous.

The necessary good electric contact can usually be produced by bringing the contacts together with some little pressure, but in order to get the best sparking effect where the circuit is broken it is desirable to separate the contacts instantly while they are still under pressure rather than to separate them in such a way that the pressure between them will gradually diminish to zero and thereafter the contacts begin to open apart.

In my present invention I have provided a make-and-break device in which the contacts are not only broken instantly that the circuit is closed, but one in which the separation of the contacts occurs instantaneously from

a closed condition in which they are pressed together with some force. This result is preferably secured by so constructing one of the contacts that it is constantly acted upon by some force which tends to move it toward the other contact, so that when the latter contact is moved against the first contact to close the circuit the contacts are held together by this force, and when the contacts separate to break the circuit the separation occurs instantaneously at a time when they are thus pressed together. One convenient way of accomplishing this result is to employ a spring of equivalent device which constantly acts on one contact to move it toward the other, the movement of said first contact toward the other being limited by a suitable stop. When said other contact is closed against the first contact to close the circuit the two contacts are pressed together by action of the spring, thus making the necessary good electrical contact, and when the latter contact moves away from the former the breaking or separation occurs while they are thus pressed together thus producing the desirable instantaneous break.

My invention may be embodied in various devices, and in order to illustrate it I have shown it as embodied in a make-and-break device for a ship's log. The invention however is not limited to use in connection with such an apparatus as will be obvious.

In the drawings Figure 1 is a perspective view showing a ship's log embodying my invention; Fig. 2 is a view of the casing for the apparatus with the cover removed showing the make and break device; Fig. 3 is a detail of the contact-closing member; Fig. 4 is a detail of the make-and-break device; Fig. 5 shows another modification of the invention; Fig. 6 is a section through the post or stud 5.

Referring first to Figs. 2, 3 and 4, the two contacts of the make-and-break device are designated by 3 and 4, and in order to avoid confusion I will refer to the contact 3 as the fixed contact and to contact 4 as the movable contact. It will be understood however that the fixed contact 3 is not necessarily an absolutely rigid and unyielding contact but only one that is fixed relative to the contact 4 which moves toward and from the contact 3. The fixed contact 3 is shown as an arm which is pivoted to a post or stud 5, and it

is acted upon by means such for instance as spring 6 which normally tends to force it toward the movable contact.

In the embodiment of the invention here-
5 in illustrated the spring 6 has one end coiled
around and secured to the stud 5 and the
other end bent to engage the upper side of
the contact 3. With this arrangement the
spring will tend to swing the contact 3 down-
wardly toward the contact 4; its movement
in this direction is limited by a suitable stop
8 which may be in the form of a pin pro-
jecting from the backing piece 9 on which
the contact is mounted.

15 The movable contact 4 is shown as pivoted
on a stud 10 which also extends from the
backing piece 9, and preferably it will be
acted upon by a suitable spring 11 tending
to move it away from the contact 3. 12 is
20 a stop which serves to limit the downward
movement of the contact 4. With this con-
struction it will be seen that the spring 6
acts to hold the contact 3 against the stop 8
with more or less pressure depending upon
25 the resiliency of the spring 6.

If the movable contact 4 is moved up-
wardly sufficiently to engage the fixed con-
tact 3 and lift it from the stop 8 the con-
tacts will be held together by the pressure
30 due to the action of the spring 6, which is
sufficient to furnish a good electrical con-
tact between said contacts. This pressure
will be maintained while said contacts are
closed together.

35 When the movable contact 4 swings down-
wardly the fixed contact 3 will follow it, said
contacts still being pressed together by the
action of the spring 6 until the contact 3
rests against the stop 8 when the pressure
40 with which the contacts are held together is
instantly removed and the separation of the
contacts occurs instantaneously and while
they are still under pressure.

The means herein shown for giving move-
45 ment to the movable contact 4 is of such
a construction that the two contacts will be
broken instantly that they are closed. The
movable contact 4 is given its closing move-
ment by means of a contact-closing member
50 12, herein shown as a cam loosely mounted
upon a stud or pivot 13. This contact-closing
member is turned about its stud thereby
to bring the cam portion thereof against the
movable contact 4 to force the latter against
55 the fixed contact 3, and suitable means are
employed to accelerate the movement of the
contact-closing member at the time that it is
about to engage with the movable contact
so as to cause the contacts to be quickly
60 closed and then instantly opened.

The means herein shown for actuating the
contact-closing member comprises a gear
wheel 14 formed with a shoulder 15 which
is adapted to engage a pin 16 which extends
65 loosely through a slot 18 in the contact-clos-

ing member, and is carried by an arm 17
loosely carried by the stud 13.

The arm 17 is acted upon by a suitable
spring, weight or other automatically oper-
ating means which tends to hold it in the po-
sition shown in Fig. 2. I have herein shown
70 for this purpose a weight 19 which is piv-
oted to the casing 20, as at 21, and which is
connected to the pin 16 by means of a
link 22.

The operation of the parts thus far de-
scribed will be apparent to those skilled in
the art, and is as follows: As the gear 14
rotates in the direction of the arrow *a*, Fig.
2, the shoulder 15 engages the end of the pin
80 16 and carries said pin and the arm 17
around with it, and as said pin reaches the
end of the slot 18 the contact-closing mem-
ber 12 is also carried around with the gear.
When the arm 17 has been carried around
85 slightly past its vertical position, as shown
in Fig. 4, the action of the weight 19 will
tend to accelerate the movement of the arm
17 and carry it quickly into the position
shown in Fig. 2, and because the pin 16 ex-
90 tends through the slot in the member 12 the
movement of the contact-closing member 12
is accelerated. The acceleration of the con-
tact-closing member occurs just prior to the
time that it engages the movable contact 4,
95 and the result is that the accelerated move-
ment of the contact-closing member 12 car-
ries said member out from engagement with
the movable contact 4 almost instantly that
it is brought into engagement therewith.
100 The contacts are thus permitted to separate
almost instantly that they are closed. Dur-
ing the accelerated movement of the arm 17
the pin 16 thereof is carried ahead of the
shoulder 15 as will be obvious, and said pin
105 and arm 17 will, after reaching the position
shown in Fig. 2, remain in such position un-
til during the rotation of the gear 14 the
shoulder 15 has again come in contact with
the pin.

110 It is desirable to make the mechanism
capable of operating when the gear 14 turns
in either direction, and accordingly I have
shown the gear 14 as having two opposed
shoulders, one the shoulder 15 above de-
scribed and the other the shoulder 25. One
shoulder is operative when the gear is mov-
ing in one direction and the other is opera-
tive when the gear is moving in the oppo-
site direction. The contact-closing member
12 is also made symmetrical in shape so that
115 it may operate in either direction. If de-
sired the movable contact 4 may carry a
friction roll 26 with which the contact-clos-
ing member engages thereby to reduce the
friction between the parts. In the present
embodiment of my invention this make-and-
break device is shown as used in conjunc-
120 tion with a ship's log, and it accordingly is
so mounted that the gear 14 may be turned
125 130

by a usual rotator which drags through the water and operates the log.

The operative parts are inclosed in a suitable casing 20 which is shown as having a hollow stem 27 extending therefrom through which extends and in which is journaled a shaft 28 to which the line 29 leading to the rotator is connected. This shaft 28 has fast thereon a pinion 30 which meshes with and 10 drives the gear 14. The casing 20 is supported by a universal joint device that it may swing both a vertical and horizontal axis to permit it to accommodate itself to the motion of the vessel. It is shown as 15 pivoted to the arms 31 of a yoke device which in turn is pivoted to turn about a vertical stud 32 carried by a bracket 33. This bracket may be secured to any suitable portion of the vessel, as for instance to the 20 taffrail 34. I have shown the stand 33 as detachably secured to the taffrails 34, it being removably supported by a base piece 35 which is screwed to said taffrail.

The complete device herein shown is 25 adapted to be used in connection with some electrical recording device, such for instance as shown in my Patent No. 749,743, dated January 19, 1904, with which device the contacts of the mechanism herein shown will 30 be electrically connected.

It will be obvious of course that the contacts 3 and 4 must be insulated from each other when they are separated, and to accomplish this both are mounted upon a block 35 9 of insulating material, and the studs 5 and 10 on which said contacts are mounted may extend through the insulating material and through the back of the case and constitute binding posts 36 to which the wires of the 40 circuit may be connected.

I have also shown a registering device mechanically connected with the rotary shaft 28 so that the rotations of the shaft may be read directly from the casing 20 if 45 desired. For this purpose the hub of the gear 14 has thereon a worm 37 which meshes with and drives a worm gear on a vertical shaft 38. Said shaft 38 has at its upper end another worm which meshes with and drives 50 a worm gear 39 on the shaft 40 of any suitable registering device 41.

The casing 20 is provided with a removable cover 42 which preferably has the sight opening 43 through which the registering 55 device 41 may be read.

In Fig. 5 I have shown another form of my invention in which the fixed contact is made resilient, and the resiliency thereof is the force which tends to move said contact 60 toward the movable contact. In this embodiment of my invention the fixed contact 300 is a resilient member which is rigidly secured to its supporting member as at 301. Said fixed contacts normally rest against a 65 stop 800 which is so situated that said mov-

able contact when resting thereagainst is under tension, the resiliency of the fixed contact holding it against the stop with more or less pressure. The movable contact 400 may be moved against the fixed contact 70 by any suitable means. It will be noted that in this form of the invention when the movable contact during its movement engages the fixed contact 300 and lifts the same from its stop 800 the resiliency of said fixed contact 300 holds the contacts together with sufficient force to produce the necessary good electrical contact between them, and that as soon as the movable contact moves downwardly this pressure is maintained until the 80 fixed contact rests on the stop 800 when the contacts instantly separate thus breaking the circuit while the contact 300 is still under tension.

Having described my invention what I 35 claim as new and desire to secure by Letters Patent is:—

1. In a make and break device the combination of a shaft, a wheel mounted on said shaft and rigidly secured thereto and carrying a pair of oppositely arranged shoulders, an arm loosely mounted on said shaft, a pin carried by said arm and extending into the path of the rotative movement of said shoulders, a contact point, a movable support 95 therefor, a symmetrical contact-closing member having an arc-shaped projection to operatively engage said support, said contact closing member being loosely mounted on said shaft between said arm and said 100 wheel and provided with a slot through which said pin extends; a stationary contact point arranged to coöperate with said first mentioned contact point, and yielding means also connected to said pin and acting on 105 said arm immediately prior to the instant that said arc-shaped projection passes through a plane passing through the point of the operative engagement of said support with said projection and the axis of said 110 shaft, to accelerate the movement of said contact closing member.

2. In a contact device a shaft, a crank arm loose on said shaft, a crank pin extending parallel to said shaft, a cam loosely 115 mounted on said shaft, the peripheral surface of which that is most remote from the axis of said shaft being arc-shaped and extending concentrically to the axis of said shaft, said cam being also provided with an 120 arc-shaped slot also concentric to the axis of said shaft and symmetrically arranged with respect to and on the same side of the axis of said shaft as said arc-shaped surface of said cam; a member rigidly secured to said shaft 125 and having a pair of shoulders, one on each side of said shaft, said crank pin extending from said arm through said arc-shaped slot and into the path of and between said shoulders, a contact point carrying arm in the 130

- path of the projecting arc-shaped surface of said cam and moved away from the axis of said shaft when operated upon by said cam, a spring tending to force said arm toward the axis of said shaft to move said arm into its position nearest the axis of said shaft when said arm is not being acted upon by said cam, a contact point mounted on said contact carrying arm, a fixed contact point coöoperating therewith, and a weight connected to said crank pin and normally holding said crank pin in alinement with the axis of said shaft and the point of engagement of said cam with said movable contact support and on that side of the axis of said shaft diametrically opposite to that of said support.
- 5 the axis of said shaft to move said arm into its position nearest the axis of said shaft when said arm is not being acted upon by said cam, a contact point mounted on said contact carrying arm, a fixed contact point coöoperating therewith, and a weight connected to said crank pin and normally holding said crank pin in alinement with the
- 10 axis of said shaft and the point of engagement of said cam with said movable contact support and on that side of the axis of said shaft diametrically opposite to that of said support.

In testimony whereof, I have signed my name to this specification, in the presence of two subscribing witnesses.

THOMAS H. McQUOWN.
